CLAIM

The ornamental design for a communications headset, as shown and described.

DESCRIPTION

FIG. 1 is a front top right perspective view of a communications headset showing our new design, the microphone boom is drawn broken away for indeterminate length;

FIG. 2 is a front view thereof;

FIG. 3 is a back view thereof;

FIG. 4 is a bottom view thereof;

FIG. 5 is a top view thereof;

FIG. 6 is a right side view thereof; and,

FIG. 7 is a left side view thereof.

The broken lines showing of the unclaimed environment forms no part of the claimed design.
